UNITED STATES PATENT OFFICE.

SOLOMON A. CAMPBELL, OF NEWTON, MASSACHUSETTS.

TIMER.

Serial No. 1,293,328.

Specification of Letters Patent.

Patented Feb. 4, 1919.

Application filed July 10, 1918. Serial No. 244,148.

To all whom it may concern:

Be it known that I, SOLOMON A. CAMPBELL, a citizen of the United States, and a resident of Newton, in the county of Middlesex and State of Massachusetts, have invented certain new and useful Improvements in Timers, of which the following is a specification.

This invention is an improved timer for internal combustion engines and is of a type wherein a rotating contact comes into wiping engagement with the successive contacts of an annular series. The invention resides primarily in the construction of this annular series of contacts. The main object of my invention is to secure a firm, effective and comparatively frictionless engagement of the rotatable contact with those of the annular series and at the same time avoid the use of a pathway, raceway, or guide including insulation material which is liable to wear, disintegrate, or become pitted, so as to give an irregular movement to the center or rotating contact. A further object is to provide a series of contacts formed of simple stamped metal parts, inexpensive to manufacture, easy and quick to assemble, and readily removed and replaced in case of wear or injury to the parts. A further object is to secure an abrupt break of the circuit and with such arcing as may be produced in the timer, occurring where it will do little or no damage and will not materially reduce the efficiency or life of the parts.

In carrying out my invention I may design various forms or embodiments varying in details of construction, without departing from the spirit of my invention or the scope thereof as defined in the appended claims. In the accompanying drawings to which reference is to be had I have shown only one embodiment which I desire to be considered in an illustrative rather than in a limiting sense.

In these drawings:

Figure 1 is an end view of a preferred embodiment, the timer shaft being shown in section.

Fig. 2 is a central longitudinal section through the casing taken substantially on the line 2-2 of Fig. 1, the shaft and rotating parts being removed.

Fig. 3 is a perspective view on an enlarged

scale of one of the series of contacts, and Fig. 4 is a perspective view on an enlarged scale of a modified form of contact.

In the form illustrated, the timer has a casing 10, of stamped or cast metal, or any other suitable material and, substantially cup-shaped in form. The casing includes a cylindrical wall portion 11, and an arm or lever 12 by means of which the casing may be oscillated to advance or retard the spark.

Extending into the casing is the timer shaft 13 carrying the rotatable contact. I have illustrated a form similar to that disclosed in the two patents of F. C. Hersee 1,203,560 and 1,264,938, but do not wish to be limited to this particular construction as the details of it form no portion of my invention and other forms of rotary contact members might be employed in my improved construction. As shown, the shaft 13 has a collar 13^a to which is pivoted an arm 14 carrying a roller 15 on one end and a projection 16 on the other end. Intermediate of the roller and the pivotal support is a coil spring 17 normally tending to force the roller outwardly in a substantially radial direction, the extent of such forced movement being limited by the engagement of the projection 16 with the collar as is shown in the drawing. Other forms of rotatable contact members which have either no movement radially of the shaft or a movement limited by means other than the casing or its contacts may be employed.

The casing carried contacts which form an important feature of my invention include a pivoted plate, tongue, or shoe 18, presenting an approximately flat inner surface disposed approximately tangentially to the path of movement of the outer part of the rotatable contact member 15. I have shown these contacts 18 as sheet metal tongues presenting parallel ears 19 at one end by means of which the contact may be connected by a pivot pin 20 to a suitable base. This base is shown as a channel-shaped strip of stamped metal 21, the side flanges of which are received between the ears 19 and support the pivot pin 20. The base is secured to the shell of the timer in any suitable manner, a very simple, inexpensive, and efficient way being by a screw 22, having its head disposed between the side flanges of the base and flattened or squared

so as to be held against rotation in respect to said base. The body of the screw extends through the base intermediate of the ends of the latter and through the peripheral wall 5 of the timer where it may be held by a nut 23. If the wall of the timer be of conducting material, such as stamped or cast metal, the base and screw are insulated from the wall, as for instance, by means of an insulation plate 24 and collar 25. The tightening of the nut 23 serves to hold all of these parts in position. The end of the contact plate 18 may be bent outwardly substantially at right angles to the body of the contact 10 so as to form a stop 26 for engaging with the end of the base 21 and limit the swinging movement of the opposite end of the contact. Between this opposite or free end and the bottom of the base and between the side flanges of the latter, may be positioned a coil spring 27 normally tending to hold the free end of the contact to the limiting position inwardly toward the timer shaft and the rotatable contact on the latter. The 15 terminal portion of the contact plate 18 is bent outwardly so as to lie beyond the path of movement of the center contact; to present an inclined surface over which the center contact may ride in case of reverse rotation in the timer shaft; and to form a definite angle or ridge from which the center contact may leave the plate 18 with an abrupt break in the circuit.

The particular device illustrated is adapted 20 to make and break the circuit four times during each revolution of the timer shaft, in other words, is adapted for a four cylinder engine. It will of course be evident that for any other number of cylinders the number and spacing of the contact shoes will be correspondingly changed. As will be understood the outer ends of the several screws 22 constitute terminals from which wires may lead to the several spark plugs while the 25 timer shaft and center contact is connected to the battery or other source of electrical energy. In operation, the parts are so adjusted that as the shaft and its contact rotates, the roller 15 will engage with the inner free surfaces of the several contact members 18, close the circuit therethrough, and in leaving them break the circuit again. The parts are so designed and adjusted that each contact plate 18 may 30 swing outwardly to a slight extent as the roller engages therewith, the comparatively long surface and slight angle preventing the pounding or injury of the contact plates 18 as the roller engages with them. During 35 this engagement, the roller may also be forced inward radially to a slight extent although preferably the main radial movement is that of the plates 18. Therefore the center contact may be so connected to the timer shaft that it will have no radial move-

ment. In the construction shown it will be noted that the stop 16 prevents the roller from swinging out radially to any material distance between successive contacts 18 and insures the proper engagement of the roller 40 with the approximately tangential surfaces of the members 18. As the members 18 are comparatively wide and the roller of a length at least equal to the width of said members, a very effective engagement of the 45 two with the free flow of current and rapid energizing of the induction coil is secured. Any slight pitting of the surfaces of the members 18 will not interfere with the free and even rolling of the contact 15 thereover 50 although most of this pitting, should any take place, will occur adjacent to the free end of the member 18 and at or beyond the portion of said member with which the roller has rolling engagements. 55

It will be evident that various changes in the details of construction of the series of contacts may be made within the scope of my invention as defined in the appended claims. One such alternative form is illustrated in Fig. 4 which construction has certain advantages in its simplicity of design and economy of manufacture. In this form, the contact plate 18^a with which the roller engages and the base 21^a which is attached 60 to the wall of the casing are integral, the relative movements of the parts being permitted by the resiliency of the material rather than by a pivotal connection as in Fig. 3. The stop for limiting the swinging of the contact plate is produced by a tip or flange 26^a on the free end rather than on the pivoted end of the contact plate. This stop is disposed between the body of the base plate 21^a and an inturned flange 26^b on the 65 end of the latter. Due to the resiliency of the metal forming these parts the bow or bent portion 27^a constitutes the spring for normally holding the contact plate in position and also constitutes the pivotal connection. 70

Having thus described my invention, what I claim as new and desire to secure by Letters Patent is:

1. A timer, having a casing, and a series 75 of contacts secured thereto, each including a channel-shaped base plate, a contact plate having side flanges at one end thereof pivoted to the flanges of said base plate, a spring intermediate of the opposite end of said plate and said base, and a stop carried by said plate adjacent to the pivot for limiting the swinging movement of said plate. 80
2. A timer, including a casing, a series of plates pivotally secured to the inner surface 85 thereof and extending circumferentially and spaced apart, means for limiting the inward swinging movement of said plates, a timer shaft, a contact pivoted thereto to swing in a substantially radial direction, and means 90

carried thereby for limiting its outward swinging movement while opposite the spaces between successive plates.

3. A timer, including a casing, a series of 5 contact plates pivotally secured to the inner surface thereof, each plate having a substantially flat straight contact surface, and having the free end thereof bent outwardly at an angle to such surface.

10 4. A timer, including a casing, a series of sheet metal plates rigidly secured thereto but insulated therefrom and presenting inwardly projecting flanges, a series of contact plates extending lengthwise of said first mentioned plates 15 and having outwardly extending flanges pivoted to said first mentioned flanges, one end of one plate being bent toward the other plate to form a stop, and a contact rotatable about the axis of the casing for engagement 20 flanges, one plate of each pair having one end bent toward the other plate for engage-

ment therewith to limit the swinging movement of the inner plate, and a central contact rotatable about the axis of said casing for engagement with said second mentioned plates in succession.

5. A timer, including a casing, a series of plates rigidly secured thereto but insulated therefrom and presenting inwardly projecting flanges, a series of contact plates extending lengthwise of said first mentioned plates 30 and having outwardly extending flanges pivoted to said first mentioned flanges, one end of one plate being bent toward the other plate to form a stop, and a contact rotatable about the axis of the casing for engagement 35 with said series of contact plates.

Signed at Boston, in the county of Suffolk and State of Massachusetts, this 2nd day of July, A. D. 1918.

SOLOMON A. CAMPBELL.
